UNITED STATES PATENT OFFICE

2,493,186

VENETIAN BLIND

Eugene Delgaudio, Brooklyn, N. Y.

Application February 19, 1946, Serial No. 648,590

2 Claims. (Cl. 160—168)

1

The present invention relates to Venetian blinds.

The primary object of the present invention is to provide Venetian blinds with slats which are readily removable from the tapes, this being accomplished without weakening of the slats. Further, in accordance with the present invention the Venetian blinds are provided with improved means for raising and lowering the blinds.

The above and other objects, features and advantages of this invention will be fully understood from the following description considered in connection with the accompanying drawings.

In the drawings:

Fig. 1 is a front perspective view of a Venetian blind embodying the present invention;

Fig. 2 is a top plan view, on a larger scale, of part of the Venetian blind of this invention;

Fig. 3 is a sectional view on the line 3—3 of Fig. 2;

Fig. 4 is a sectional view on the line 4—4 of Fig. 3;

Fig. 5 is a view of an end portion of a slat of modified form.

Referring now to the drawings in detail, the Venetian blind 10 of the present invention comprises the head rail 12, the slat-tilting rail 14, the slats 16, the bottom rail 18, and the usual laddered tapes 20. Also, as usual, the Venetian blind 10 includes a mechanism 22 for tilting the rail 14, said mechanism being operated by the cord 24.

In accordance with the present invention, the cords for raising and lowering the slats 16, pursuant to the raising and lowering of the bottom rail 18, do not extend through holes in the slats, and for this reason the slats can be easily removed from the laddered tapes 20 for cleaning or for other purposes and can be readily reinserted in position, without removing the cords. As here shown, the slats 16 are provided with recesses 26 in their opposite ends, and a single length of cord 28 is arranged in relation to the slats at the opposite ends thereof in the recesses 26 so that the slats can be readily removed from the laddered tapes 20 and from engagement with said cord without requiring unfastening of the cord from the lower rail 18 or from any other part of the blind.

As shown in the drawings, one end of the cord is knotted or otherwise attached to the bottom rail 18 at one end thereof as indicated at 30 and the opposite end of the cord is similarly fastened at the opposite end of rail 18 as indicated at 32. The cord extends upwardly from the first men-

2

tioned end of rail 18, across the adjacent ends of the slats, to and through an opening 34 in the head rail 12, and passes over a guide pulley 36 longitudinally of said head rail to a fixture 38, indicated in Fig. 1 and illustrated in further detail in Figs. 2 to 4. The cord passes over the guide pulley or roller 40 mounted in said fixture, is looped as indicated at 42 and passes over a guide roller or pulley 44 and then longitudinally to and over a guide pulley 46, passing downwardly from said guide pulley 46 through an opening 48 in the head rail, and from the latter across the ends of the slats to the point 32 at which the cord is fastened to the bottom rail 18. It will be noted that the cord 28 extends from the looped portion 42 thereof in opposite directions over the guide rollers 40 and 44, longitudinally of the head rail 12 in the groove 52 thereof to points near the opposite ends, respectively, of the blind so that the vertically extending portions 28a and 28b of the cord 28 are disposed at the opposite ends, respectively, of the slats and are thus disposed outwardly of the laddered tapes 20. The provision of the end recesses in the slats is preferred, but it is within the scope of the present invention to omit the recesses since the portions 28a and 28b of the slat raising cord can be disposed adjacent to the opposite ends, respectively, of the slats. Thus the slats can be devoid of openings between the opposite ends of the slats and can also be devoid of recesses in the ends of the slats. Also it will be understood that the recesses 26 when provided in accordance with the preferred embodiment of the invention, can be of various forms. Thus, for example, as illustrated in Fig. 5 the recesses in the end of the slat indicated at 16a can be provided with a constricted opening 54 to hold the cord releasably in said recess or any other suitably shaped recess can be provided as desired.

Referring now more particularly to the fixture 38 in which the guide rollers 44 are mounted it will be observed that said fixture is fastened to the bracket 56 by which one end of the slat tilting rail 14 is pivotally mounted in a well understood manner, said bracket being provided as usual with a slot 58 leading to a bearing portion 60 for the bearing pin of rail 14. Fixture 38 includes the lateral spaced sides 62 in which the pins 64 and 66 for the pulleys or rollers 40 and 44, respectively, are secured. The opposite sides 62 of fixture 38 are connected by a portion 68, which may be integral with said sides, which cooperates with the pivoted locking member 70 for holding the looped portion of the cord 28 against movement, whereby to hold the bottom rail 18 releasably in

its adjusted position. It will be understood that the looped portion of the cord 28 is released from its locking engagement by movement of said portion to the right, viewing Figs. 1 and 3 and that said looped portion is automatically locked in position when said looped portion is released following its operation for raising or lowering the blinds. The fixture 38 may be secured to bracket 56 in any suitable way, for example by spot-welding the inner end portions 72 of the fixture sides 32 to the bracket.

It will be understood that the invention may be embodied otherwise than as herein specifically illustrated and described and that various changes in the details of construction and in the arrangement of parts may be made without departing from the underlying idea or principles of this invention.

Having thus described my invention, what I claim and desire to secure by Letters Patent is:

1. In a Venetian blind having a head rail, a bottom rail, a slat-tilting rail, laddered tapes connected to said bottom rail and to said tilting rail, and a plurality of slats carried by said laddered tapes; a cord connected at its opposite ends to said bottom rail and to said head rail for raising and lowering said bottom rail whereby to raise and lower said slats, the vertical portions of said cord being disposed at and confronting the opposite free ends, respectively, of said slats and movable endwise of said slats to a position clear of engagement therewith whereby to permit the removal of the slats from the blind without unfastening the cord from said bottom rail, said cords normally engaging the opposite free ends, respectively of said slats for releasably holding the latter in aligned relation on said laddered tapes, said head rail being provided with means including guide pulleys, there being end guide pulleys adjacent the opposite ends, respectively, of said head rail and a pair of intermediate guide pulleys positioned between said end guide pulleys and both located adjacent each other near one of said end guide pulleys, and the cord having portions extending from the upper ends respectively of said vertical cord portions in opposite directions therefrom over said end pulleys, respectively, and longitudinally of said head rail and downwardly therefrom in engagement with said intermediate guide pulleys, respectively, forming an intermediate looped portion of the cord for use in operating said cord to raise and lower said bottom rail of the blind and to correspondingly raise and lower said slats, said head rail having an apertured portion, one of said end pulleys

and said intermediate guide pulleys being disposed in said apertured portion, one of said vertical cord portions entering said apertured portion for engagement with said one end pulley therein, and said looped portion extending downwardly through said apertured portion inwardly of said one vertical cord portion.

2. In a Venetian blind which comprises a plurality of slats and means including a rail for raising and lowering said slats, a single length of cord operatively connected in the blind for raising and lowering said rail, said cord being operatively connected to said rail and extending upwardly therefrom transversely of the slats at the opposite free ends, respectively, of said slats in confronting relation to said ends, respectively, then horizontally in opposite directions toward a point between the opposite ends of the blind, and then downwardly to provide a doubled cord-operating portion, said cords being freely movable away from the adjacent ends, respectively, of said slats, and rollers carried by the blind for guiding the cord for movement in said directions, said blind having a head rail and said cord-guiding means being carried by said head rail, said means including end rollers adjacent the opposite ends, respectively, of the blind and a pair of rollers located adjacent each other at said point between the opposite ends of the blind, said head rail having an apertured portion at said point, said pair of rollers and one of said end rollers being disposed in said apertured portion, said cord extending upwardly adjacent a free end of said slats through said apertured portion, and said doubled portion thereof extending downwardly therethrough inwardly of said free ends.

ENGENE DELGAUDIO.
